UNITED STATES PATENT OFFICE.

UDO DITTMAR, OF FREIBURG IM BREISGAU, BADEN, GERMANY.

DRAWING MECHANISM FOR SPINNING FIBROUS MATERIALS.

Application filed August 16, 1927, Serial No. 213,353, and in Germany January 24, 1927.

The present invention relates to a drawing-mechanism for spinning fibrous materials, the mechanism preferably comprising additional bottom- and top-rollers which on their working faces are a small distance apart from each other even without the interposition of a sliver or roving. The invention essentially consists therein, that the additional bottom-rollers have been so constructed as to pass through for a more or less great part of the drawing-frame so as to act together with a plurality of top-rollers and are actuated independently from each other, preferably by one of the main bottom-rollers.

The single drive of the additional bottom-rollers passing through more or less extensively is preferably effected with the aid of gear-wheels, chain or the like.

Between the main bottom-roller and the additional bottom-roller a reversing gear-wheel, which may be mounted in a special support or carrier, may be provided, the reversing gear-wheel being preferably adjustable to the gear-wheel of the actuating or driving main bottom-roller.

The gear-wheel drive may advantageously be arranged in the interior of a standard, and be rendered dust- and dirt-proof by covers of sheet-metal or such like. For the purpose of supporting the gear-wheel drive for the additional bottom-rollers an additional preferably adjustable slide which simultaneously may serve as cover for the bearing-pivots of the intermediate and hindmost main bottom-rollers may be provided and fitted to the standard or carrier within which the drive for the bottom-rollers is contained.

A constructional example of the subject-matter of the present invention has been illustrated in the accompanying drawings in which

Fig. 1 represents a view of a part of a device according to the invention,

Fig. 2 shows a section along the line 2—2 of Fig. 1 on a scale somewhat enlarged,

Fig. 3 is a plan-view of a part of a device in accordance with the present invention.

Referring more particularly to the draw-

ings *a* represents standards upon each of which a slide *b*, which may be clamped in position by a screw *c*, has been provided. *d* is a further slide attached to the slide *b* with the aid of the screws *f* which also render it possible to adjust the said further slide. This slide carries the pivots of the gear-wheels *g*, *h*. Hereby it has been rendered possible to adjust the mesh of the gear-wheels against each other. The slide *d* is covered by the metal-sheets *k*, *m* whereas the former is made to cover the bearings for the main bottom-roller *i*¹ appertaining to the gear-wheel *i* and the main bottom-roller *n*. For this purpose it has been provided with gaps *o*, *p*. *n*¹ represents top-rollers for the main bottom-roller *n*. By means of the gear-wheel drive *i*, *g*, *h* the additional bottom-roller *h*¹ appertaining to the gear-wheel *h* is actuated. These additional bottom-rollers are of such short length that they are not subjected to torsion by the effect of the drive. They are, however, of sufficient length so as to extend across a number of appertaining top-rollers *g*. Owing to this special drive it has become possible to give these additional bottom-rollers a very small diameter, so that they may be placed very closely to the delivery-rollers *r*¹, *r*².

The additional bottom-rollers *h*¹ and their top-rollers *g* have preferably been by dimensioning their working surfaces as set forth in my pending application Ser. No. 37,963 so constructed as to allow the longer fibres to slip through, so that the creation of a positive pressure, as with the other pairs of main drawing- or stretching-cylinders or rollers, is avoided. Owing to the disposition of the gear-wheels *g*, *h* in a special additional slide *d* it is possible, to adjust the roller *i*¹ appertaining to the gear-wheel *i* and the corresponding top-roller *s* to the pair of delivery-rollers *r*¹, *r*², without changing the distance between the additional pair of rollers *h*¹, *g* and the pair of delivery-rollers *r*¹, *r*². The additional bottom-roller *h*¹ has been so placed that its upper vertical line is on a higher level than the clamping point between the delivery rollers *r*¹, *r*² and the clamping point between the main bottom-

roller i^1 and its top-roller s . By these means it is attained that, if the additional pair of rollers h^1 is so constructed as to be free from clamping properties, the fibres or sliver or roving to be stretched or drawn by the pair of delivery cylinders meet upon the gliding surface of the additional bottom-rollers with a certain support and further that thereby the thin top-rollers co-operating with the thin additional bottom-rollers cannot be raised if tensions in slivers or rovings or fibres take place. The working-surfaces of the additional bottom-rollers and their top-rollers are preferably of such design that they are a small distance apart, even if there is no sliver or roving between them. Between each two standards a a plurality of toprollers n, s, q, r^2 have been provided, separated from each other by a bracket-block t . In the left and intermediate standards, Fig. 1, a drive has been indicated, whereas the right standard illustrates the fact, that the additional bottom-rollers h^1 are independent from each other.

Having thus explained the nature of my invention and described a way of making and using same, although without attempting to set forth all of the forms in which it may be made or all of the modes of its use, what I claim is:—

1. In a drawing-frame for spinning-machines a plurality of pairs of main drawing-rollers in combination with a plurality of additional bottom-rollers which are shorter than the main drawing-rollers and driving means for each said additional bottom-roller.

2. In a drawing-frame, according to claim 1, the construction of the additional, shorter bottom-rollers of such nature that they are suitable to be actuated by one of the bottom-rollers of the pairs of main drawing-cylinders.

3. In a drawing-frame according to claim 1, the construction of the additional shorter bottom-rollers of such nature, that they are suitable to be actuated by one of the main bottom rollers of the pair of main drawing-rollers by means of gear-wheels.

4. In a drawing-frame according to claim 1, the addition of a plurality of special top-rollers to each of the additional shorter bottom-rollers.

5. In a drawing-frame according to claim 1, the addition of a plurality of special top-rollers to each of the additional shorter bottom-rollers which at the working-point are separated by a small distance, even if there is no sliver present between the additional bottom-rollers and their top-rollers.

6. In a drawing-frame according to claim 1, a plurality of gear-wheels on one of the main bottom-rollers, a gear-wheel on each additional bottom-roller and a reversing gear-wheel between each gear-wheel of the

main bottom-roller and the gear wheel of the additional bottom-roller.

7. In a drawing-frame according to claim 1, a plurality of gear-wheels on one of the main bottom-rollers, a gear-wheel on each of the additional bottom-rollers, and a reversing gear-wheel, which is relatively adjustable to the gear-wheel of the main bottom-roller, between each gear-wheel of the main bottom-roller and the gear-wheel of the additional bottom-roller.

8. A drawing frame for spinning-frames with a plurality of pairs of main drawing-rollers in combination with a plurality of additional bottom-rollers each with an independent drive, the said additional bottom-rollers being shorter than the main drawing-rollers and the standards for carrying the said rollers, a plurality of gear-wheels on one of the main bottom-rollers, a gear-wheel on each of the additional bottom-rollers, and a reversing gear-wheel between each gear-wheel of the main bottom-roller and the gear-wheel of the additional bottom-roller, in which connection the said gear-wheels appertaining to each other have been installed within one of the said standards of the drawing-mechanism or drawing-frame.

9. A drawing-frame for spinning-frames, with a plurality of pairs of main drawing-rollers in combination with a plurality of additional bottom-rollers each with independent drive and each being shorter than the main drawing-rollers and the standards for carrying the said rollers, a plurality of gear-wheels on one of the main bottom-rollers, a gear-wheel on each of the additional bottom-rollers, a reversing gear-wheel between each gear-wheel of the main bottom-rollers and the gear-wheel of the additional bottom-rollers, the disposition of the said gear-wheels within the said standards or carriers, and a cover which is of a suitable design to protect the gear-wheels from dust.

10. In a drawing-frame for spinning-frames according to claim 8, a slide adjustable relatively to the gear-wheel of the main bottom-rollers, the said slide being adapted to form a bearing for said additional bottom-rollers and a said reversing gear.

11. In a drawing-frame for spinning-frames according to claim 8, a slide being adjustable to the gear-wheel of the main bottom-roller, of suitable construction to form a bearing for one of the additional reversing gear-wheels and provided with a cover of suitable construction to protect the gear-wheels from dust and dirt.

12. In a drawing-frame for spinning-frames, according to claim 8, a slide being adjustable to the gear-wheel of the main bottom-roller of suitable construction to form a bearing for an additional bottom-roller and a reversing gear-wheel, and

which is further suitable to cover the bearing of a main bottom-roller in the standard.

13. In a drawing-frame for spinning-frames according to claim 8, a slide being
5 adjustable to the gear-wheel of the main bottom-roller of suitable construction to form a bearing for one additional bottom-

roller and a reversing gear-wheel, and which is further suitable to cover the bearing of each of a plurality of main bottom-rollers. 10

In testimony whereof I have affixed my signature.

UDO DITTMAR.
